BATH MAT

Maurice H. Kraines, Los Angeles, and Robert L. Unkrich,
Long Beach, Calif.; said Unkrich assignor to said
Kraines

Filed Dec. 26, 1961, Ser. No. 68,071

Term of patent 14 years

(Cl. D9—6)

We claim:

The ornamental design for a bath mat, substantially as shown.
